PREWELT CEMENTING AND FORMING
MACHINEEric A. Holmgren, Beverly, Mass., assignor to
United Shoe Machinery Corporation, Flemington, N. J., a corporation of New Jersey

Application January 12, 1945, Serial No. 572,445

4 Claims. (Cl. 12—51)

This invention relates to machines for treating prewelt shoe uppers prior to the lasting operation and is shown as embodied in a machine for simultaneously straightening or flattening the welt and applying a coating of adhesive to its sole-attaching surface.

So-called "prewelt" shoes are manufactured extensively in infants' sizes and, prior to the lasting operation, the welt is stitched to the upper in such a position that it lies snugly against the upper and thus renders it difficult to present the upper to the lasting instrumentalities for operation thereon. Accordingly, it is customary to pass the welt between pressure rolls which assist in taking out any kinks or wrinkles and which in the performance of this operation draw the upper away from the welt so that the welt will stand out in a plane such as that which it will assume when it is attached to a sole, thus facilitating the presentation of the upper to the wipers of the bed lasting machine, for example. It is also customary to apply to the attaching surface of the welt, as a part of the same operation, a coating of cement which will be utilized for temporarily securing the welt to the margin of a sole to which it ultimately will be fastened permanently, as by stitches. Commonly, machines for this operation have been provided with coating feed rolls rotatable upon parallel axes for engagement with the opposite surfaces of the welt. The end surface of one of these rolls necessarily engages the outer surface of the upper and in the hands of a careless operator may accidentally scar it, especially around the toe end of the shoe. With these conditions in mind, it is an object of the invention to provide an improved machine for simultaneously coating the attaching surface of the welt in a prewelt shoe upper prior to the lasting operation and straightening or flattening the welt.

In accordance with this object, the illustrated machine embodies a coating apparatus to which the welt is presented by means of a frusto-conical roll rotatable about an axis which is nearly vertical so that the base of the inverted cone supports the welt, while the wedge-shaped periphery thereof serves to separate the welt and the upper. Coating with this mechanism is a work-supporting or molding finger engageable with the inside of the upper to hold the work against the supporting roll with the latter firmly seated in the welt crease, and this finger is carried on a slide so that it may be separated from the rolls to facilitate the introduction of a piece of work. An operator-controlled mechanism is provided

for moving the slide and, in accordance with an important feature of the invention, is so arranged that, when the slide, and hence the finger, is in its inner, operative position, the operating mechanism locks it there against displacement.

This and other features of the invention will best be understood from a consideration of the following specification taken in connection with the accompanying drawings, in which

10 Fig. 1 is an angular view of the work-engaging parts of the machine;

Fig. 2 is an exploded view of a finger-carrying slide and its guideway;

15 Fig. 3 is a side elevation of these same parts, showing them in the position which they occupy when engaging a shoe upper, with the slide locked in this position, and

20 Fig. 4 is a side elevation, with parts broken away and in section, and illustrating the finger-carrying slide as moved to its work-releasing position.

Designed for the treatment of work W including an upper 10 to which there has been stitched a welt 12, the structure includes a cylindrical cement-applying roll 14 mounted on a driven shaft 16 contained in the frame 18 of a machine of the type illustrated in Letters Patent of the United States No. 2,038,561, granted April 28, 1936, upon the application of J. B. Hadaway.

30 Cement is supplied to the periphery of this roll by a series of rolls, one of which is shown at 20.

Associated with the applying roll 14 is a welt-supporting or feed roll 22 of inverted frusto-conical shape which is rotatable about a substantially vertical axis and is supported and driven by a mechanism 24 described in said patent. In order to separate the supporting roll 22 from the applying roll 14 when introducing a piece of work, there is provided a treadle-controlled cable 40 26 attached to a pivoted arm 28 which supports the frusto-conical roll. As the wedge-shaped periphery of this supporting roll 22 enters the welt crease, it spreads apart the welt 12 and the upper 10 while cooperating with the applying roll 14 to apply pressure to the welt, thereby to take the wrinkles out of it. A guard 29 (Fig. 1) is provided for the front of the roll 22.

It will be seen at once that, in order for the supporting roll to be most effective, the work 50 must be guided against lateral deviation from its intended path, thereby to keep the wedge-shaped periphery of the supporting roll 22 seated in the welt crease, and this is effected by a molding finger 30 having a rounded end 32 which engages the lining or the inside of the upper (Fig.

3) and is effective to hold the work firmly against the wedge-shaped edge of the supporting roll 22 to separate the welt from the upper while also molding or forming the margin of the upper inwardly for engagement with the bottom of the last. This finger 30 is attached to a depending rod 34 carried at the outer end of a curved arm 36 (Fig. 2) which has a reduced portion 38 (Fig. 4) with a beveled end held on a slide 40 by means of a clamp plate 42. This slide is positioned and supported in a slideway 44 adjustably carried on the frame 18 of the machine by means of a curved arm 46 fastened to a depending bracket 48 by a screw 49 passing through a vertical slot in the arm. The bracket is attached to the machine frame. The slideway 44 has a groove 50 for receiving the slide 40, and this groove is deepened at 52 for a purpose which will later appear. The slide is held in the slideway by means of cover plates 54 and 56. Movement of the slide to carry the molding finger 30 away from the applying rolls, so as to facilitate the introduction or removal of a piece of work, is effected by a crank arm 60 having a pin 62 entering a vertical groove 64 formed in an upward extension 66 of the slide. This crank arm 60 is secured by a draw bolt 68 (Fig. 4) to a rockshaft 68 journaled in the side of the slideway above the deepened portion 52 of the groove and having on its outer or near end an arm 70 normally urged in a clockwise direction by means of a spring 72 attached to the frame at one end and to a pin 74 in the arm at its other end. This spring 72 is therefore effective to hold the crank arm 60 in the position illustrated in Figs. 1, 2 and 3 so that it lies in the slideway 44 substantially at the bottom of the deepened portion 52 of the groove therein with its crank pin 62 in the vertical groove 64 of the slide. In this position, it is effective to lock the slide against any force tending to move it outward. The slide 40 has a lateral recess 63 (Fig. 2) to receive the crank arm 60 and the cover plate 56 is cut away at 65 to allow said arm to emerge from the guideway as in Fig. 4.

Operation of the crank arm 60 to move the slide outward against the tension of the spring 72 is effected by means of a slotted arm 76 integral with or secured to a cross shaft 78 which is journaled in a lug 80 on the underside of the guideway 44. This shaft 78 has clamped to its far end a lever 82 connected by a chain 84 to a treadle (not shown) such as the one connected to the cable 26. When the treadle is depressed the arm 70 will be rotated counterclockwise, the crank arm 60 tilted upwardly and the slide 40 will be moved to the left. A suitable amount of slack is provided in this latter cable in order that the molding finger 30 may be moved out of engagement with the work before the feed rolls 14 and 22 are separated or, conversely, in order that the finger may be brought against the work before the feed movement starts.

In operating the machine, assuming that the treadle has been depressed, the welt 12 will be separated manually from the upper 10 at some convenient point and moved into position between the feed rolls. The treadle will then be released and the molding finger 30 brought into engagement with the inner surface of the upper, or the lining as the case may be, thus bottoming the roll 22 in the welt crease. Then the feed movement starts and a coating of cement will

be applied to the attaching surface of the welt, the work being held inverted with the welt gripped between the two rolls. As a result, there will be an effective straightening of the welt and a molding of the associated upper into a condition in which the upper will cling to the last and the welt will stand out ready for presentation of the upper to the lasting machine. As the supporting roll engages successive portions of the welt crease, there will be no danger of scarring the upper because its action is the same on different shoes irrespective of the size and exact contour of the upper and because the top of the roll is substantially in the plane of the welt crease.

Having thus described my invention, what I claim as new and desire to secure by Letters Patent of the United States is:

1. In a machine for operating on prewelt shoe uppers, means for applying cement to the sole-attaching surface of the welt, welt-crease-entering means for supporting the welt in cooperative relationship to said applying means, molding means engaging the inside of the upper to hold the upper in engagement with said welt-crease-entering means, a movable support for the molding means, and means for positively holding said support in such a position that the said molding means is locked in engagement with the upper.
2. In a machine for operating on prewelt shoe uppers, a roll for applying cement to the sole-attaching surface of the welt, a frusto-conical supporting roll rotatable about an axis angularly related to the axis of the first roll and with the base of said roll supporting the welt in engagement with the cementing roll, an upper-entering finger for holding the work in engagement with the periphery of the supporting roll, and operator-controlled means for withdrawing said finger to permit removal of the work.
3. In a machine for operating on prewelt shoe uppers, a cement-applying roll the bottom of which is adapted for engagement with the attaching surface of a welt secured to an upper held in inverted position, crease-entering means for supporting the welt in engagement with said roll, an upper-supporting member subtending a portion of said cementing roll and arranged to hold the crease of the upper in firm engagement with the supporting means, a slide carrying said member, and operator-controlled means for moving said slide constructed and arranged, in one position, to lock the slide in such position that the upper-supporting member holds the work positively against disengagement from the crease-entering means.
4. In a machine for operating on prewelt shoe uppers, a cementing roll, a supporting roll having a wedge-shaped periphery, a slideway, a slide therein, said slide having a groove angularly related to the direction of movement of the slide, a finger supported by said slide for engagement with the inside of the upper to hold the welt crease against the supporting roll, a crank arm cooperating with said groove and adapted to rest in the slideway substantially normal to said groove to hold the finger in work-engaging position, and operator-controlled means for rotating said crank arm to move the slide to carry the tool away from the work.
